US0D1007687S

(12) **United States Design Patent** (10) Patent No.: **US D1,007,687 S**
(45) Date of Patent: ** Dec. 12, 2023

(54) **VENTILATORY THERAPY DEVICE**

(71) Applicant: **Löwenstein Medical Technology S.A.**,
Luxembourg (LU)

(72) Inventor: **Anne Wonsyld**, Hamburg (DE)

(73) Assignee: **LOEWENSTEIN MEDICAL
TECHNOLOGY S.A.**, Luxembourg
(LU)

(**) Term: **15 Years**

(21) Appl. No.: **35/509,698**

(22) Filed: **Jun. 4, 2020**

(80) **Hague Agreement Data**

Int. Filing Date: **Jun. 4, 2020**

Int. Reg. No.: **DM/208713**

Int. Reg. Date: **Jun. 4, 2020**

Int. Reg. Pub. Date: **Jun. 26, 2020**

(51) **LOC (14) Cl.** **24-02**

(52) **U.S. Cl.**

USPC **D24/164**

(58) **Field of Classification Search**

USPC D24/187-190, 107, 164, 185, 231, 232
CPC . A63B 23/18; A61M 16/0006; A61M 16/024;
A61M 16/00; A61M 16/0066; A61M
16/0816; A61M 16/14; A61M 16/20

See application file for complete search history.
